US0D1022197S

(12) **United States Design Patent** (10) **Patent No.:** **US D1,022,197 S**
(45) **Date of Patent:** **** Apr. 9, 2024**

(54) **ENDOSCOPE**

(71) Applicant: **Auris Health, Inc.**, Redwood City, CA (US)

(72) Inventors: **Juan B. Bajana Merizalde**, San Francisco, CA (US); **Thomas G. T. Brisebras**, San Francisco, CA (US); **Fabien Y. Schmitt**, Redwood City, CA (US); **Matthew C. Miller**, Cincinnati, OH (US); **Stephen M. Christopher**, Philadelphia, PA (US); **Shawn C. Snyder**, Greendale, IN (US); **Evan N. Stambler**, Cincinnati, OH (US); **Clinton W. Denlinger**, Cincinnati, OH (US); **Samuel J. Malanowski**, Menlo Park, CA (US)

(73) Assignee: **Auris Health, Inc.**, Redwood City, CA (US)

(**) Term: **15 Years**

(21) Appl. No.: **29/759,096**

(22) Filed: **Nov. 19, 2020**

(51) LOC (14) Cl. **24-02**

(52) U.S. Cl.

USPC **D24/138**

(58) **Field of Classification Search**

USPC **D24/137, 138**

CPC **A61B 1/00172; A61B 1/00009; A61B 1/00042; A61B 1/00043; A61B 1/00057; A61B 1/00066; A61B 1/00105; A61B 1/00117; A61B 1/00128; A61B 1/00165; A61B 1/00181; A61B 1/00183; A61B 1/0052**

(57) **CLAIM**

The ornamental design for an endoscope, as shown and described.

DESCRIPTION

FIG. 1 is a front perspective view of an endoscope; FIG. 2 is a rear perspective view thereof; FIG. 3 is a front end view thereof; FIG. 4 is a rear end view thereof; FIG. 5 is a right side elevational view thereof; FIG. 6 is a left side elevational view thereof; FIG. 7 is a top plan view thereof; FIG. 8 is a bottom plan view thereof; and, FIG. 9 is a rear perspective view, showing the endoscope in an in use configuration.

The broken lines depicting a cable in FIG. 9 depict environmental subject matter that forms no part of the claimed design. The remaining broken lines depict portions of the endoscope that form no part of the claimed design.

1 Claim, 8 Drawing Sheets
